UNITED STATES PATENT OFFICE

94,040

DESIGN FOR A BRACELET OR SIMILAR ARTICLE OF JEWELRY

John M. Miller and George F. Fenton, Providence,
R. I., assignors to The Progressive Ring Com-
pany, Providence, R. I., a corporation of Rhode
Island

Application July 24, 1934, Serial No. 52,683

Term of patent 7 years

To all whom it may concern:

Be it known that we, John M. Miller and George F. Fenton, both citizens of the United States, and both residing at Providence, in the county of Providence and State of Rhode Island, have invented a new, original, and ornamental Design for a Bracelet or Similar Article of Jewelry, of which the following is a specification.

In the accompanying drawing which forms a part of this specification,

Figure 1 is a front view of a bracelet or similar article of jewelry embodying our new design,

Figure 2, a top plan view of the same,

Figure 3, a section of the same on line 3—3 of Figure 2 drawn to an enlarged scale, and

Figure 4, a front view of a portion of the bracelet disclosed in Fig. 1, showing the light reflecting depressions on an enlarged scale.

The design is characterized by light reflecting depressions formed on the surface of the bracelet.

We claim:

The ornamental design for a bracelet or similar article of jewelry, as shown and described.

JOHN M. MILLER.
GEORGE F. FENTON.
